FLUORESCENT LIGHTING FIXTURE
SERVICING IMPLEMENTRobert T. Riker and Joseph H. Molat,
Brooklyn, N. Y.

Application January 24, 1945, Serial No. 574,304

6 Claims. (Cl. 294—20)

1

Our invention is directed toward a novel and improved appliance for servicing fluorescent lighting fixtures, and has for one of its objects to provide an appliance of the character described which shall be so constructed and arranged that defective elongated glass tubes of the type customarily employed in fluorescent lighting fixtures and which fixtures are hung from the ceiling or disposed at other points beyond reach may be readily removed and replaced by an operator from the floor without the necessity of using ladders and without the necessity of removing the fixture.

Another object of our invention is to provide a novel and highly improved appliance for servicing fluorescent lighting fixtures by means of which the elongated glass tubes which comprise such fixtures may be removed and replaced without damage to the fixture or the tube and which at the same time shall be provided with means for readily removing and replacing defective starters.

Further objects and advantages of our invention will become apparent from the description or will hereinafter be pointed out.

In the accompanying drawing,

Fig. 1 is a side elevational view, partly sectional, of a fluorescent lighting fixture servicing appliance constructed and arranged in accordance with our invention;

Fig. 2 is a front elevational view of the upper portion thereof;

Fig. 3 is an enlarged view of a portion of the appliance shown in Fig. 1; and

Fig. 4 is an enlarged detail view of a portion adjacent the bottom end of the appliance shown in Fig. 1 and illustrating its function and purpose.

Referring now in detail to the drawing we have shown an appliance for servicing fluorescent fixtures constructed and arranged in accordance with our invention and comprising a pair of substantially vertically disposed arms 10 and 11 of resilient or spring material and which may be attached at their lower ends to a suitable base support 12 by any desirable attaching means, such as by the screws 13. The said arms 10 and 11 are preferably arranged so that they normally spread apart, tapering in an upward direction. At the upper ends of the arms 10 and 11 there are fixedly attached, in any well known manner, jaw members 14 and 15 respectively. It is noted that the said jaw members 14 and 15 are arcuate in shape and are normally spaced apart a sufficient distance to freely embrace diametrically opposite sides of an elongated glass tube T of the standard type customarily em-

2

ployed in fluorescent lighting fixtures. It is further noted that the said jaw members 14 and 15 extend longitudinally in a horizontal direction parallel to the axis of the said tube T and that they project for a predetermined distance beyond said arms 10 and 11 in both directions. It is noted that the length of the jaw members 14 and 15 may be varied in accordance with the length of the tube. The said jaw members 14 and 15 are provided on the inner surfaces thereof with layers 20 of material which is preferably of the type which is relatively soft so as not to injure the glass tube when the jaws 14 and 15 grip the same and they are additionally of the type which will frictionally hold the said glass tube T so that it may be rotated axially for the purposes of removing and replacing the same.

It is thus seen from the above described construction that when it is desired to remove a glass tube T from a fluorescent fixture for the purpose of replacing the same or for other reasons, it is merely necessary to pass the jaws 14 and 15 freely on diametrically opposite sides of the said tube and then cause the said jaws to be brought together to grip the said tube therebetween and then by slightly turning the gripped tube axially, it may be freed and removed from its supporting brackets.

In accordance with our invention the following means may be employed for causing the said jaws 14 and 15 to be moved toward each other against the normal action of the spring arms 10 and 11.

Fixed to the arm 10 is a bracket 25 to which there is pivotally attached one end of a rod member 26, by means of the pivot 27. The free end 26a of the rod 26 is screw threaded and passes freely through and projects beyond a slotted opening 24 in the arm 11. Fixed to the base member 12 is a rigid supporting arm 31, having an integral upstanding portion 31a. Attached to the said portion 31a by the rivets 34, is a leaf spring 33, so curved as to have one end 33a thereof freely contactively engaging the arm 11 below said rod 26, and the opposite end 33b thereof freely contactively engaging the arm 11 at a point adjacent the jaw 15. Disposed near said portion 31a and normally parallel thereto is a rigid member 29 pivotally mounted, at its lower end, by means of a pivot 30, on the supporting arm 31.

The spring 33, the rigid portion 31a and the rigid member 29 are each provided with slotted openings 35, 37 and 28, respectively, to permit free angular movement of the rod 26 projecting therethrough.

It is seen from the above description that when

the rigid member 29 is pivotally moved in a clockwise direction as viewed from Fig. 1 and 3, it will cause the arm 10 to move toward the arm 11 due to the fact that the rod 26 is provided with an abutment nut 32. The rigid portion 31a and the spring 33 interposed between the said arm portion 31a and the arm 11 causes the simultaneous movement of the arm 11 toward the arm 10. It is noted that the free slidable end 33b of the spring 33 is disposed near the jaw 15 so as to exert its pressure in the area of the said jaw 15.

In order to be able to effectively use the appliance of our invention from the floor without having to employ step ladders or chairs or stools, we mount the base support 12 for the arms 10 and 11, on a suitable hub member 36 to which there is attached a long rod 40 of any desired suitable length for the convenience and efficiency. To pivotally move the rigid member 29 as above described in a clockwise direction to close the jaws 14 and 15 we provide the rod 40 with a pair of spaced fixed bracket members 42 and 43 through which we slidably pass another rod 50, the upper end 50a of which is outwardly angularly bent, as shown. The said end portion 50a of the rod is pivotally attached to an outwardly angularly bent and forked portion 60 of the rigid member 29 by means of the pivot 55. Any suitable handle may be provided at the lower end of the rod 50. For convenience we have shown a lever 57 pivoted at one end to the rod 40 by the pivot 58. The lever 57 is provided with a slotted opening 59 and the rod 50 is attached to the lever 57 by means of a pivot 61 operating in the slot 59.

It is thus seen from the above description that when it is desired to close the jaws 14 and 15 it is merely necessary to grasp the lever 57 and turn the same in a clockwise direction to its dotted line position 57'. This will slidably pull the rod 50 downwardly to pivotally move the arm 29 to close the jaws 14 and 15.

A set screw 80 carried by one of the brackets 43 may be employed to lock the rod 50 in any desired position.

It is often necessary, when servicing fluorescent lighting fixtures, to remove and replace defective starters. To this end, we have incorporated, in our appliance, the following means whereby to readily remove these defective starters without using step ladders, chairs or stools and at the same time that defective tubes are being replaced.

Attached to the bottom end of the rod 40 is a cylindrical member 70 which is preferably made of rubber or the like resilient material and which is provided with an opening 71 substantially similar in size and contour to that of the standard type starter S, shown in Fig. 4 of the drawing. The said opening 71 is designed to frictionally receive therein and grip the starter S so that it may be manipulated to pry it loose from its socket or holder. The said member 70 may be attached to said rod 40 in any suitable manner, such as by the screws 73 shown in Fig. 4.

While we have shown, in the drawing, the jaws 14 and 15 as consisting of a single unit, we may, if desired, construct each jaw of two parts spaced from each other along the length of the glass tube T. Such construction might prove more efficient in cases where the said tubes T are of relatively greater length by affording a greater gripping area.

In accordance with the provisions of the patent statutes, we have herein described the principle and operation of our invention, together with apparatus which we now consider to represent

the best embodiments thereof, but we desire to have it understood that the structure shown is only illustrative and that the invention can be carried out by other means. Also, while it is designed to use the various features and elements in the combination and relations described, some of those may be altered and others omitted without interfering with the more general results outlined, and the invention extends to such use.

Having described our invention, what we claim as new and desire to secure by Letters Patent is:

1. A fluorescent lighting fixture servicing implement comprising a first spring arm and a second spring arm constituting a pair of substantially vertically disposed spring arms normally spaced apart, a relatively long handle, a support for said arms disposed at one end of said handle so that the upper ends thereof will be free, an arcuate jaw member fixed to said free end of each spring arm, said jaw members being in opposed relationship and adapted to clamp and hold between them the elongated glass tube of said fluorescent lighting fixture when said spring arms are urged towards each other, and means for causing said spring arms to move toward each other, said last named means comprising a substantially horizontally disposed rod member having one end thereof pivotally mounted on said first arm and the opposite end passing freely through an opening in said second arm, an abutment on said rod member, adjacent the free end thereof, an extending bracket portion on said support, a substantially vertically disposed rigid member pivotally mounted at the lower end thereof on said bracket and having an opening adjacent the upper free end thereof through which said horizontal rod member freely passes, said upper free end of said rigid member being disposed between said second arm and said abutment, so that pivotal movement of said rigid member in a direction toward said abutment will cause the resilient movement of said first arm toward said second arm.

2. A fluorescent lighting fixture implement according to claim 1 in which the said jaw members are provided with a layer of felt or the like resilient material to prevent injury to the said glass tube during the clamping action.

3. A fluorescent lighting fixture implement according to claim 1 in which the said jaw members are so disposed that the axes of said jaw members are substantially parallel to each other and to the axis of said glass tube.

4. A fluorescent lighting fixture implement according to claim 1 in which the said jaw members extend longitudinally for a relatively long distance along said tube.

5. A fluorescent lighting fixture servicing implement according to claim 1 in which the said jaw members are substantially horizontally disposed and in which each of said jaw members extend for a substantial distance on opposite sides of the spring arm to which it is attached.

6. A fluorescent lighting fixture implement according to claim 1 in which the said bracket is provided with a vertically disposed rigid extension disposed between said rigid member and said second arm, an opening in said rigid extension through which said horizontally disposed rod member freely passes, and a spring interposed between said second arm and said rigid extension.
